UNITED STATES PATENT OFFICE.

ALBERT L. KRAUS, OF PEABODY, MASSACHUSETTS, ASSIGNOR TO ALBERT L. KRAUS, OF PEABODY, AND EDWARD L. MILLETT, OF BEVERLY, MASSACHUSETTS, COPARTNERS DOING BUSINESS UNDER THE FIRM NAME AND STYLE OF KRAUS, MILLETT & COMPANY, OF PEABODY, MASSACHUSETTS.

BUFFING-WHEEL.

1,238,925.

Specification of Letters Patent.

Patented Sept. 4, 1917.

Application filed October 26, 1915. Serial No. 58,030.

To all whom it may concern:

Be it known that I, ALBERT L. KRAUS, a citizen of the United States, and resident of Peabody, in the county of Essex and State 5 of Massachusetts, have invented new and useful Improvements in Buffing-Wheels, of which the following is a specification.

My invention relates to buffing wheels and its principal object is to provide a wheel 10 adapted to carry a removable, relatively narrow buffing strip of felt or similar material so mounted that all the well understood advantages of a wheel made entirely of felt or similar yielding material are obtainable at a greatly reduced cost.

Referring to the drawings,—

Figure 1 is a side elevation of my improved wheel;

Fig. 2 is a section on the line 2—2, Fig. 20 1; and

Fig. 3 is a detail view of the seat hereinafter described.

A is a hub adapted to fit upon the usual wheel shaft of a buffing machine and having 25 external screw threads *a* at one end. Upon the opposite end of said hub and preferably formed integral therewith as shown, is a relatively thin metal disk B having upon its inner face and near its periphery 30 a laterally extending annular rib B'. The said disk is further provided on its inner face and in proximity to said rib B' with a laterally extending annular flange B² formed with projections B³ spaced apart as 35 shown in Figs. 2 and 3.

C is another metal disk provided with a central opening for the hub A on which it is movably mounted and having an annular rib C' corresponding to the rib B' of the 40 disk B and a flange C² formed with projections C³ spaced apart corresponding to the flange B² of the disk B. The disk C is so positioned on the hub A that the projections C³ of the flange C² are located in the 45 space between the projections B³ of the flange B², as clearly shown in Fig. 3, so that the said two flanges while non-engaging, form in effect a single continuous flange which serves as a flexible seat for the buff- 50 ing strip D.

The said buffing strip D which is preferably of the form shown, is of felt or other

similar yielding material having grooves *d* in which the oppositely disposed holding ribs B' and C' fit when the strip is seated 55 on the rest formed by the flanges B² and C². It will be observed that the buffing strip D has a peripheral portion substantially wedge-shaped in cross section, and is further provided with a groove adjacent to the 60 holding disks B and C, whereby said strip can be readily deflected out of the plane of rotation and thus become adapted for use in buffing and polishing portions of the work not readily operated upon by the usual buff- 65 ing strip, *e. g.* at the juncture of the upper and sole of the shoe. Around the hub A is a spring E which engages the inner faces of the disks B and C and, when the parts are in normal position shown in the draw- 70 ings, is held under compression by the nut F which is threaded on to the hub A to lock the movably mounted disk C in position. The spring E permits the disk C and strip D to be firmly held in position without sub- 75 jecting the strip to undue or excessive pressure, so that a strip of soft and readily compressible felt may be firmly held between the disks without bringing said disks so close together as to impair or destroy the flexible 80 character of the seat formed by the flanges B² and C². The said spring E also serves to force the disk C away from the disk B to permit removal of a worn out strip.

It will I believe be clear that because of 85 its flexible seat the buffing strip D is enabled to yield to the work and so obtain all the advantages of a wheel made entirely of felt or similar material at a very low cost as compared with that of such solid wheel. 90 When it becomes necessary to renew the strip D, the nut F is loosened whereupon the spring E forces the disk C away from the disk B permitting the old strip D to be removed and a new strip placed and locked 95 in position without removing the wheel from the shaft.

I claim:

1. A buffing wheel comprising a hub, a pair of disks on said hub spaced apart and 100 one at least being movably mounted thereon, said disks having oppositely disposed annular ribs and oppositely disposed annular non-engaging flanges, a buffing strip

seated on said flanges and having grooves adapted to receive said ribs, a normally compressed spring between said disks, and a nut threaded on said hub to lock said disks in position with said buffing strip therebetween.

2. A buffing wheel comprising a hub, a pair of disks on said hub spaced apart and one at least being movably mounted thereon, said disks having oppositely disposed annular ribs and oppositely disposed lateral projections spaced apart, the projections of one disk located in the spaces between the projections of the other disk, a buffing strip seated on said projections and having grooves adapted to receive said ribs, a normally compressed spring between said disks and a nut threaded on said hub to lock said

disks in position with said buffing strip therebetween.

3. A buffing wheel comprising a buffing strip of yielding material having a groove whereby said strip can be readily deflected out of the plane of rotation.

4. A buffing wheel comprising a buffing strip of yielding material having a peripheral portion substantially wedge-shaped in cross section, and a groove whereby the strip can be readily deflected out of the plane of rotation.

Signed by me at Peabody, Massachusetts, this 23rd day of October, 1915.

ALBERT L. KRAUS.
